DESIGN FOR A CROSS STAND

Robert H. Ischinger, Reading, Pa.

Application June 11, 1945, Serial No. 120,018

Term of patent 14 years

(Cl. D29—23)

To all whom it may concern:

Be it known that I, Robert H. Ischinger, a citizen of the United States of America, residing at 216 North 6th Street, Reading, in the county of Berks and State of Pennsylvania, have invented a new, original, and ornamental Design for a Cross Stand, of which the following is a specification, reference being had to the accompanying drawings, forming part thereof.

Figure 1 is a top plan view of the cross stand embodying my new design.

Fig. 2 is a front elevational view,
Fig. 3 is a side elevational view,
Fig. 4 is a rear elevational view, and
Fig. 5 is a front perspective view thereof.

I claim:

The ornamental design for a cross stand, as shown.

ROBERT H. ISCHINGER.
